CLAIM

The ornamental design for a machine center, as shown and described.

DESCRIPTION

FIG. 1 is a perspective view of the machine center, showing the present design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is an enlarged view of a portion in FIG. 6.

The bottom view forms no part of the claimed design and is therefore omitted.

The dash-dash broken lines in the drawings illustrate portions of the machine center that form no part of the claimed design. The dot-dash broken lines in FIGS. 6 and 7 illustrate boundaries of the enlarged portion that form no part of the claimed design.
